UNITED STATES PATENT OFFICE.

ALFRED LITTAUER, OF ASBURY PARK, NEW JERSEY.

DENTAL MOUTH-MIRROR.

SPECIFICATION forming part of Letters Patent No. 778,981, dated January 3, 1905.

Application filed November 19, 1903. Serial No. 181,779.

To all whom it may concern:

Be it known that I, ALFRED LITTAUER, of the city of Asbury Park, county of Monmouth, and State of New Jersey, have invented certain new and useful Improvements in Double Mirrors, of which the following is a full, clear, and concise specification.

My invention relates to dental instruments, and more particularly has to do with a new and improved double or compound reversible mirror, which is simple in construction, cheap of manufacture, and capable of being readily cleansed or otherwise manipulated.

Referring to the accompanying one sheet of drawings, which forms a part of this specification, Figure 1 is a transverse sectional view of Fig. 2 on the line 2 2, and Fig. 2 is a plan view of the mirror with the handle shown broken off.

In its preferred form the device comprises two oppositely-disposed disks of glass silvered on one side in the usual manner, one of the disks being flat to constitute a plane mirror A for one side and the other being slightly concave to constitute an enlarging-mirror B, as indicated in the drawings. The two mirrors are preferably of the same size and shape and are placed back to back and permanently united by means of a layer or mass of hard cement C, which conveniently extends very close to the edges of the disks. The kind of cement used is immaterial, so long as it serves to unite and hold the two disks firmly together and is sufficiently dense not to have a tendency to absorb moisture. The double mirror as thus formed may be used as a pocket-mirror without a handle, if desired; but for convenient use as a dental instrument I form a groove around the edge of the layer of cement and provide a pair of clamping members D, adapted to fit in the groove and extend more than half-way around the disks, as indicated in Fig. 2, the construction being such that the double mirror may be readily inserted and removed from the holding-frame

and when inserted will be securely held with either side up, as may be desired. The groove may be formed by milling, or the quantity of cement used to form the layer C may be proportioned so as to leave a crevice between the 5c mirrors. In either case the crevice or groove formed will serve the purpose of providing a seat for the spring members D. The latter, however, represent only one of many possible forms of holding-frames, and it is preferred 55 by reason of its simplicity and the facility whereby the mirror may be reversed or removed.

It is to be understood that variations may be made in the form or shape of the double 60 mirror above described and that the groove may be formed in the edges of the glass disks as well as in the cement or that the holding-frame may be extended to entirely surround the mirrors, all without departing from the 65 spirit and scope of my invention.

Having described my invention, what I claim is—

1. As a new article of manufacture, a double mirror comprising single mirrors of substantially the same size and contour placed back to back and united by an intermediate layer of cement disposed between them, the peripheral edge of said double mirror being formed to receive a holding-frame. 75

2. As a new article of manufacture, a double mirror comprising single mirrors placed back to back and united by an intermediate layer of cement disposed between them, in combination with a peripheral groove around said layer of cement and a holding-frame adapted to seat in said groove. 80

In testimony whereof I have signed my name, in the presence of two subscribing witnesses, this 13th day of November, 1903.

ALFRED LITTAUER.
